UNITED STATES PATENT OFFICE.

HARRY ROBERT NORTHOVER, OF WINNIPEG, MANITOBA, CANADA.

COMBINED GAS-LEVER CASE AND STAND OR MOUNTING FOR COLT-TYPE AUTOMATIC GUNS.

1,237,083.

Specification of Letters Patent. Patented Aug. 14, 1917.

Application filed June 19, 1916. Serial No. 104,530.

To all whom it may concern:

Be it known that I, HARRY ROBERT NORTHOVER, subject of the King of Great Britain, residing at 217 Graham avenue, Winnipeg, 5 Manitoba, in the Dominion of Canada, have invented certain new and useful Combined Gas-Lever Cases and Stands or Mountings for Colt-Type Automatic Guns, of which the following is a specification.

10 Automatic or machine guns of the "Colt" type embody a gas-operated lever (technically known as the "gas-lever") which is pivoted underneath, and swings below, the muzzle end of the barrel, and is adapted to transmit movement to the belt-feeding, loading and firing mechanism at the breach of the gun.

When such a gun is in operation, the gas-lever makes its angular rearward and return 20 motions below the barrel after every shot, and therefore the weapon can only be fired automatically from a trench or like confined position, or from behind a sand-bag or other cover, provided there exists a sufficient 25 space or clearance underneath the front or muzzle end of the gun to allow for the free or unimpeded movement of the said lever, while if the lever should be fouled by falling earth, displaced sandbags or the like, the automatic 30 action of the gun is stopped until such time that the obstruction has been removed. In other words, the gun can only operate automatically in positions where proper working clearance for the gas-lever can be provided 35 and maintained, and for this reason its general utility or adaptability under active service conditions is somewhat restricted.

In order to obviate or remedy this disadvantage and to enable the gun to be aimed, 40 traversed and fired through loop-holes, between sand-bags, over trench-parapets or in other confined positions without possibility of the gas-lever being obstructed, it is proposed, according to the present invention to 45 apply to or embody in a Colt or like gun, an attachment or fitting which serves as a case or cover for the gas lever and may also form a part of, or be associated or combined with, a folding or collapsible stand or 50 mounting that is transportable bodily with the said gun and provides for the supporting of the same on the "muzzle-pivoted" principle when in action.

In the accompanying drawings I have shown the preferred form of carrying out my 55 invention as applied to a combination attachment which embodies a gas-lever case and a collapsible stand or "attack-tripod" for use in connection with a Colt gun.

Figure 1 is a side elevation of the said 60 attachment, showing the leg-members of the stand secured in their folded positions against the sides of the gas-lever case to facilitate transport.

Fig. 2 is an end elevation of the same. 65

Fig. 3 is a longitudinal vertical section of the attachment, taken on the dotted line x , Fig. 8.

Fig. 4 is another end view, similar to Fig. 2, but the upper part of the attachment is 70 shown in section on the dotted line x^1 , Fig. 3, and the view also illustrates how the legs of the stand are adapted to automatically extend or swing outward, when the fastenings whereby they are normally secured 75 against the slides of the lever-case are disengaged.

Fig. 5 is a plan view, partly in section, of the connection between the leg members of the stand and the top of the case. 80

Fig. 6 is a side elevation of the attachment and Fig. 7 is an end view, showing the legs of the stand extended into their gun-supporting positions.

Fig. 8 is a plan of Fig. 7. 85

Fig. 9 is a detail view of one of the leg-fastenings partly in section on the dotted line x^2 , Fig. 7, and

Fig. 10 is a detail section on the dotted line x^3 Fig. 6. 90

The same letters of reference indicate corresponding parts in the several figures of the drawings.

In the construction shown in these figures, the gas-lever cover part of the attachment 95 consists of a flat-sided metal box or case a which is adapted to be detachably fitted or secured below the front parts of the barrel and body of the gun so that it will completely inclose the gas-lever. The body of 100 the case is semi-circular in elevation, its edges being curved to a radius struck from the center of the gas-lever pivot, while its width and depth are such as will admit of the gas-lever oscillating freely therein; the 105 dimensions and weight of the said body be-

ing, however, kept as small as possible consistent with the said lever having sufficient working clearance.

This gas-lever case may be detachably anchored or secured to the gun by any convenient means which will provide a rigid or immovable connection between the two, but in the preferred construction represented in the drawings, the top of the said case is furnished with a lid or hood b which is hinged along one side and is adapted to embrace or clip over the front part of the barrel of the gun; the edge of the said lid farthest from the hinge b^1 being provided with spring catches b^2 that snap into suitable engagements in the corresponding side of the case-body when the lid is closed over the barrel, but can be forced out of such engagements by using the nose of a cartridge-bullet or the like as a lever when it is required to dismount the attachment from the gun. The flanged ends b^3 , b^4 of this lid are shaped at b^5 , b^6 to fit or seat closely around the barrel and the rear end of the body of the box also is shaped to fit under the frame of the gun; suitable vent-holes being formed in the lid and (if necessary) in the box-body to admit air for cooling the inclosed part of the barrel, and also to provide for the free escape of the powder gases that are discharged through the barrel-vent into the interior of the said box when the gun is firing. A clearance is also made at b^7 in the rear of the box for the gas-lever connecting link to work through.

To obviate any possibility of the attachment being displaced in the direction of the length of the gun, either or both flanged ends b^3 , b^4 of the lid may be made to engage behind or between certain of the cooling or radiating webs of the barrel of a Colt gun, while angular or lateral displacement is rendered impossible by the fact that the upper sides and rear end of the body of the box are made to seat upon or embrace the square-sectioned or flat-sided fore end of the gun-body; and in addition, the box may be provided with studs or similar positive anchoring devices which are adapted to engage holes or recesses in the bottom-plate of the gun.

Thus the gas-lever case, when attached or secured by fastenings such as above described, is rigidly anchored against movement in any direction relatively to the gun, and completely incloses the gas-lever at all positions of the latter. The gun can therefore be set up for firing in practically any conceivable position or situation, for as the depth of the attachment (as designed for a Colt gun) is only approximately six inches measured from the under-side of the bottom plate to the bottom of the case, while its width is the same as that of the gun itself,

the depending box occupies or takes up only a minimum of space below the muzzle end of the barrel. Further, the attachment does not add materially to the weight of the gun so that it can be left in position on the latter without affecting its portability, and it does not interfere with the firing of the weapon from an ordinary tripod or like mounting. Moreover, the attachment positively obviates any liability of the gas-lever being fouled or obstructed when the gun is in action, while it does not detrimentally affect the normal rate of fire or the action of the gun in any way.

An additional and important advantage of the case is that it can be readily associated or combined with a folding or collapsible stand arrangement which provides a "muzzle-pivot" mounting whereby the gun to which the said case is attached can be quickly set up or brought into action and elevated, depressed, traversed and fired without the aid of the usual service tripod or support. To provide for this, the case is combined with an arrangement of jointed legs or struts which—when extended—will adequately support the muzzle end of the gun through the medium of the attached case, and will yet admit of a gunner elevating, depressing or traversing the gun by correspondingly lowering, raising or laterally swinging the breech end, which is held and supported by the gunner's hands when the gun is being aimed and fired.

According to the preferred form of the stand arrangement which is represented in the drawings, the gas-lever case is permanently combined with a system of folding or collapsible legs to which the gun is pendulously connected through the medium of the said case in such a manner that the suspended gun is capable of universal movement relative to the stand when the latter is extended or erected for use. The said gun can thus be elevated, depressed and traversed or trained with the greatest ease and rapidity on moving targets, while the stand part of the arrangement provides an adjustable or adaptable but rigid support or mounting which enables the gun to be quickly set up and effectively brought into action or employed in confined situations or on rough or uneven ground, and which when erected, is not liable to be disturbed or deranged by recoil or other shocks from the firing of the gun. On the other hand, when the mounting is folded or collapsed, its main members lie closely against the sides of the gas-lever case so that the gun and its mounting can be readily transported or carried into or out of action by a single man; thereby greatly facilitating the use of Colt-type machine guns for supporting infantry attacks, or for consolidating captured posi-

tions owing to the fact that a gun to which the attachment is applied can be easily carried forward with the attacking troops and set up and brought into action on practically any ground or in any position in a minimum of time.

In the said illustrated construction, the top cover or lid *b* of the lever-case which closes over the barrel of the gun is connected with a transverse bar or cross piece *c* which constitutes a member of the stand or mounting and to whose opposite extremities, the upper ends of a pair of angularly-adjustable legs or struts *d*, *d*¹ are hinged in such a manner that they can either be folded flat against the opposite sides of the case as shown in Figs. 1 and 2, or spread outward to any suitable angle (within certain limits) relative to the said sides as shown in Figs. 6, 7 and 8. The case (together with the gun to which the case is attached) is thus hung from the upper cross piece and between the two folding and adjustable legs, and in order to insure that the said case and gun shall always hang in a vertical plane when the stand is erected, irrespective of the angles which the legs or struts themselves assume, and also to enable the case and gun to be moved in any direction for elevating, depressing or traversing purposes, the connections between the case and the cross-piece and also between the cross-piece and the lugs are preferably constructed in the following manner:

35 A circular opening *e* is formed in the top-lid or cover *b* of the case, and is fitted with a freely-rotatable disk or turn-table *e*¹ which carries a pair of headed studs *e*² (Figs. 4 and 5) that engage with curved slots *e*³ formed in a plate *e*⁴ which is fixed inside the said lid *b*, underneath the said opening *e*, this arrangement constituting a joint whereon the case may be swiveled so as to swing horizontally in either direction (and over a wide angle of movement) relative to the cross-piece *c*. Thus, when the stand is erected, this swivel connection allows the gunner to freely traverse the gun by moving the breech end laterally to the right or left; the whole stand meanwhile remaining stationary or rigid.

The above-mentioned disk or turn-table *e*¹ is hinged or pivoted to the upper cross-piece or transverse member *c* of the stand by a joint-pin *c*¹ whose center coincides with the longitudinal center of the case and is at right angles to the said cross-piece (see the sectional view, Fig. 4). The case and gun hang or are suspended from the top of the stand through this joint, which, without interfering with the traversing of the said gun about the joint *e*, *e*¹ insures that the said gun will normally hang in a vertical plane when the stand is erected, irrespective

of the angles in which the adjustable legs *d* or struts may be placed when the gun is set up on irregular or uneven ground, or in confined situations.

The outer ends of the cross-piece or transverse member of the stand are turned upward or formed with vertical lugs *c*² to which are pivoted laterally-projecting lugs *c*³ wherein the upper ends of the legs *d*, *d*¹ are jointed; the horizontal pivots *c*⁴ of the said lugs constituting fulcra whereon the said case may be swung in a vertical plane to admit of the elevation or depression of the gun. Thus, the swiveling connection *e*, *e*¹ between the case and the cross piece of the stand and the horizontal pivots *c*⁴ between the cross piece and the lugs *c*³ together constitute a universal joint system that enables the suspended or pendulously-hung gun to be freely moved in any direction relative to the stand *c*, *d*, *d*¹, for traversing, elevating or depressing the said gun as may be required.

The pivot-studs *c*⁴ whereby the upper ends of the folding and adjustable legs *d*, *d*¹ are jointed to the lugs *c*³, are disposed at right angles to the pivots connecting the said lugs with the cross-piece *c*, and suitable stops (such as *d*³) are embodied in these leg-joints for limiting the outward angular movement or lateral spread of the said legs.

To enable the mounting, when extended, to stand up against recoil and other firing shocks transmitted in the direction of the longer axis of the gun to the upper part of the said mounting each leg is furnished with a U-shaped or double branched foot *f*; the two feet being disposed parallel to one another so that when positioned for use, their extremities engage the ground and provide four widely separated points of support (two on either side of the gun) to insure the longitudinal and lateral stability of the mounting. The extremities of the branches of these feet may be pointed or pronged and are preferably fitted with hinged attachments *f*¹ which can be turned into positions (as indicated by dotted lines in Fig. 7) where they will bear upon the surface of the ground when the legs are extended and assist in keeping the structure rigid.

Preferably the straight middle portions *f*² of the feet *f* are contained in sleeves or elongated bearings *d*⁴ attached to the lower ends of the legs, which not only prevent the feet from twisting about the axis of the said legs, but also provide for their being folded inwardly and upwardly against the inner sides of the legs, so that when the mounting is closed or collapsed and the legs are folded against the sides of the gas-lever case, the feet will also lie against the case sides, in substantially the same plane as the said legs, as shown in Fig. 2. By then temporarily

connecting or fastening the legs to the sides of the case (such as by means of sliding catches g that are mounted on the said legs and are adapted to be engaged with grooved 5 fittings or keepers g^1 on the case sides) the feet as well as the legs themselves can be held in these folded positions, whereas by merely withdrawing the catches from their 10 keepers, the folding parts of the mounting are freed and can be immediately extended for supporting the suspended gun in the firing position.

The hinged feet are influenced by suitably-applied springs h which, on the legs 15 being unfastened and spread away from the case, act to automatically turn down the hinged feet into line with the said legs; suitable stops h^1 , h^2 being arranged in connection with the feet (as shown in detail in 20 Fig. 10) for limiting their movement under the springs so that they cannot turn outwardly beyond the center-lines of the legs or struts with which they are respectively associated. The springs h , in addition to 25 turning down the feet as described, also function to automatically and simultaneously swing the legs of the stand outward; this being due to the fact that when the catches g are disengaged, the pointed ends 30 of the feet are constrained (by the angular movement which the said feet make under the action of their springs) to travel down the sides of the case as illustrated in Fig. 4 and thus force the legs away from the 35 case into their gun-supporting positions. This arrangement enables the gun to be set up for action in a minimum of time, as when a man carrying the gun and attachment (with the legs folded and fastened to the 40 case) arrives at a position from which he desires to open fire, he has merely to lift the catches g from the fittings g^1 when the legs will fly outward and the feet will simultaneously spring into line therewith, as 45 shown in Fig. 7. The extended stand has then only to be placed on the ground and the gun can be brought into action immediately.

I wish it to be understood that I do not 50 limit myself to the universal joint arrangement above described for connecting the suspended gas-lever case with the legs of mounting, as I may adopt any other system of joints or pivotal connections which 55 will admit of the gun being swung in horizontal and vertical planes for traversing, elevating and depressing the same and which also will admit of the said gun with its gas-lever case-attachment hanging in a vertical 60 plane irrespective of the angles taken up by the legs or struts when the mounting is erected.

A Colt-type gun furnished with an attached case or cover for inclosing the oscillating

gas-lever such as above described 65 must obviously be provided with some means for manually operating the said lever from the breech end of the gun, and for this purpose, I prefer to employ an arrangement such as described in my prior Patent, 70 No. 1,207,612, granted December 5, 1916.

Having described my invention, what I claim and desire to secure by Letters Patent is:—

1. A mounting of the character specified 75 for Colt-type automatic or gas-operated guns, comprising a case or box adapted to be fixed underneath the front or gas-lever end of the gun, so as to inclose the gas-lever; and a collapsible stand for supporting said 80 gun, with which said case has a universal connection, thereby to provide for traversing, elevation and depression of the gun.

2. A mounting of the character specified 85 for Colt-type automatic or gas-operated guns, comprising a case or box adapted to be fixed underneath the front or gas-lever end of the gun, so as to inclose the gas-lever, 90 said case having a hinged lid or cover; and a collapsible stand for supporting said gun, with which said lid has a universal connection, thereby to provide for traversing, elevation and depression of the gun.

3. A mounting of the character specified 95 for Colt-type automatic or gas-operated guns, comprising a case or box consisting of a body adapted to be fixed underneath the front or gas-lever end of the gun, so as to inclose the gas-lever, said body having its rear end shaped to fit under the frame of 100 the gun, and a lid or cover hinged along one side to the adjacent side of said body and arranged to directly clip over the gun barrel, said cover having flanged ends which are shaped to fit closely around the gun 105 barrel.

4. A mounting of the character specified 110 for Colt-type automatic or gas-operated guns, comprising a case or box consisting of a body adapted to be fixed underneath the front or gas-lever end of the gun, so as to inclose the gas-lever, and a lid or cover 115 hinged along one side to said body and provided at its opposite side with spring catches for engagement with said body.

5. A mounting of the character specified 120 for Colt-type automatic or gas-operated guns, comprising a case or box consisting of a body adapted to be fixed underneath the front or gas-lever end of the gun, so as to inclose the gas-lever, said body having its rear end shaped to fit under the frame 125 of the gun, and a lid or cover hinged along one side to said body and provided at its opposite side with spring catches for engagement with said body, said cover having its ends shaped to fit closely around the gun barrel.

6. A mounting of the character specified for Colt-type automatic or gas-operated guns, comprising a case or box adapted to be fixed underneath the front or gas-lever 5 end of the gun, so as to inclose the gas-lever; and a stand for supporting said gun embodying a system of folding and laterally-extending legs from which said case is suspended and with which it has a universal 10 connection, thereby to provide for traversing, elevation and depression of the gun.

7. A mounting of the character specified for Colt-type automatic or gas-operated guns, 15 comprising a case or box adapted to be fixed beneath the front or gas-lever end of the gun, so as to inclose the gas-lever, and provided with a cross-piece having a rotatable connection thereto; and a stand for supporting 20 said gun embodying a system of legs from whose upper ends said cross-piece is suspended, said leg ends having compound pivotal connections with the ends of the cross-piece; whereby traversing, elevation 25 and depression of the gun are permitted.

8. A mounting of the character specified for Colt-type automatic or gas-operated guns, comprising a case or box adapted to be fixed beneath the front or gas-lever end 30 of the gun, so as to inclose the gas-lever; and a stand for supporting said gun, embodying a system of laterally-extending legs from which said case is pivotally suspended, feet pivoted to the lower ends of said legs, 35 said legs and feet adapted to be folded against the sides of the case, and means for retaining the same in folded position.

9. A mounting of the character specified for Colt-type automatic or gas-operated 40 guns, comprising a case or box adapted to be fixed beneath the front or gas-lever end of the gun, so as to inclose the gas-lever; and provided at its opposite sides with keepers; and a stand for supporting said 45 gun, embodying a system of laterally-extending legs from which said case is pivotally suspended, feet pivoted to the lower ends of said legs, said legs and feet adapted to be folded against the sides of the case, 50 and catches carried by said legs for engagement with said keepers to hold said legs and feet in folded position.

10. A mounting of the character specified for Colt-type automatic or gas-operated 55 guns, comprising a case or box adapted to be fixed beneath the front or gas-lever end of the gun, so as to inclose the gas-lever; and a stand for supporting said gun, embodying a system of laterally-extending legs 60 from which said case is pivotally suspended, feet pivoted to the lower end of said legs and feet adapted to be folded against the sides of the case, means for retaining the same in folded position, and springs for

automatically extending said legs and feet 65 when said retaining means are released.

11. A mounting of the character specified for Colt-type automatic or gas-operated guns, comprising a case or box adapted to be fixed beneath the front or gas-lever end 70 of the gun, so as to inclose the gas-lever; and provided at its opposite sides with keepers; a stand for supporting said gun, embodying a system of laterally-extending legs from which said case is pivotally suspended, feet pivoted to the lower ends of 75 said legs, said legs and feet adapted to be folded against the sides of the case, and catches carried by said legs for engagement with said keepers to hold said legs and feet 80 in folded position, and springs for automatically extending said legs and feet when said catches are disengaged.

12. A mounting of the character specified for Colt-type automatic or gas-operated 85 guns, comprising a case or box adapted to be fixed beneath the front or gas-lever end of the gun, so as to inclose the gas-lever; and a stand for supporting said gun, embodying a system of legs from which said 90 case is suspended, said legs having inverted U-shaped feet connected to their lower ends, to steady the gun against firing shocks.

13. A mounting of the character specified for Colt-type automatic or gas-operated 95 guns, comprising a case or box adapted to be fixed beneath the front or gas-lever end of the gun, so as to inclose the gas-lever; and a stand for supporting said gun, embodying a system of legs from which said 100 case is pivotally suspended, U-shaped feet pivoted to the lower ends of said legs, to steady the gun against firing shocks, said feet being foldable upwardly into inoperative position against the sides of the case, 105 and springs for simultaneously moving said legs outwardly and said feet downwardly into operative position.

14. A mounting of the character specified for Colt-type automatic or gas-operated 110 guns, comprising a case or box adapted to be fixed underneath the front or gas-lever end of the gun, so as to inclose the gas-lever, said case provided at its top with a turn-table and with a cross-piece secured thereto and having up-turned ends; and a stand for supporting said gun, embodying a system of legs from whose upper ends said cross-piece is suspended, said leg ends having compound pivotal connections with the up-turned ends of the cross-piece. 115

15. A mounting of the character specified for Colt-type automatic or gas-operated guns, comprising a case or box adapted to be fixed underneath the front or gas-lever 120 end of the gun, so as to inclose the gas-lever, said case provided at its top with a turn-table and with a cross-piece, said cross-piece 125

having a transverse pivotal connection with said turn-table; and a stand for supporting said gun, embodying a system of legs from whose upper ends said cross-piece is suspended, said leg ends having compound pivotal connections with the ends of the cross-piece.

In testimony whereof I have hereunto set my hand in presence of two subscribing witnesses.

HARRY ROBERT NORTHOVER.
